UNITED STATES PATENT OFFICE

165,760

SELECTIVE MERCHANDISE VENDING MACHINE

Alva R. Jones, Morris, Ill., assignor to The Northwestern Corporation, Morris, Ill.

Application August 18, 1951, Serial No. 16,370

Term of patent 14 years

(Cl. D52—3)

To all whom it may concern:

Be it known that I, Alva R. Jones, a citizen of the United States, and resident of Morris, in the county of Grundy and State of Illinois, have invented a new, original, and ornamental Design for a Selective Merchandise Vending Machine, of which the following is a specification, reference being had to the accompanying drawings, forming a part thereof:

Fig. 1 is a perspective view of a selective merchandise vending machine, showing my new design;

Fig. 2 is a side elevational view of the same selective merchandise vending machine; and

Fig. 3 is a top plan view of the same.

The rear of the machine is substantially plain.

I claim:

The ornamental design for a selective merchandise vending machine, substantially as shown and described.

ALVA R. JONES.
